UNITED STATES PATENT OFFICE.

IRA IRVING INMAN, OF HARTFORD CITY, INDIANA.

FASTENING OR SEALING DEVICE FOR BURIAL CASKETS.

Application filed April 28, 1926. Serial No. 105,246.

The purpose of the present invention is to provide, in a fastening or sealing device for burial caskets of improved construction, improved means for hermetically sealing the 5 cover or lid of the casket.

Another purpose is to provide a casket including a sealing device, of improved construction, and one which is exceedingly durable. In other words, the casket as herein 10 disclosed has lasting qualities, and is substantially impervious to the various destructive elements, such as air, earth, water, or time.

Still another purpose is to provide a casket including its sealing device, constructed 15 of any suitable material, preferably aluminum or copper, it being a particular aim to employ pressed steel surfaced or finished in porcelain enamel.

A further purpose is to provide, in hermetically sealing the cover or lid, a composition 20 of rubberized or rubber treated fabric (for instance, similar to gasket material), utilized in a marginal groove of substantial concave cavity on the under side of the lid 25 or cover for the purpose of conforming to the marginal rolled rim, thus affording a casket of air and water tight character.

A further purpose is to provide an improved fastening consisting of a member 30 passing through the adjacent marginal rolled rims of the cover and the body of the casket, including a lever with cams engaging the under face of the marginal rolled rim of the body of the casket, for drawing the two 35 rims closely together, to insure a fluid-tight joint. It is the aim to construct these fastenings of non-corrosive metal, the number of fastenings to be used varying according to the size of the casket.

40 It is also the aim to construct all the fixtures to be used on the casket of material similar to the material of which the fastening devices are constructed.

It is to be understood that the particulars 45 herein given are in no way limitative and that while still keeping within the scope of the invention, any desired modifications of detail and desired proportions may be made in the apparatus according to circumstances.

50 The invention comprises further features and the combination of parts, as will be here-

inafter set forth, shown in the drawings, and claimed.

In the drawings:

Figure 1 is a transverse sectional view 55 through a casket of improved construction.

Figure 2 is an enlarged fragmentary view of the lid or cover for the casket.

Figure 3 is an enlarged detail sectional view through the marginal rolled rims or 60 flanges of the body of the casket and the cover.

Figure 4 is a detail view of one of the bolts constituting a member of the fastening 65 device.

Figure 5 is an enlarged detail perspective view of the lever with its cam adapted to be mounted upon the bolt, the lever with its cams acting for cooperation with the marginal rolled rim or flange of the body of the 70 casket.

Referring to the drawings, 1 designates a casket which may be any size and shape and constructed of any suitable metal, preferably 75 pressed steel heavily coated or surfaced preferably with porcelain enamel, rendering the body of the casket more durable, due to the fact that such surfacing or coating of porcelain enamel carries with it substantial resisting qualities to the elements of the earth, 80 it also being the aim to afford a casket having special merit, for instance, it being reasonable in cost, and the construction is such as to insure compactness in transportation, in that the lid and the body of the casket may 85 be nested, rendering the casket convenient for army and navy use, the nesting of the cover or lid and the body of the casket enabling the casket to be readily put into storage.

90 The casket may be made into marble or wood finish, and otherwise ornamented, as may be found desirable.

The casket has a cover 2. The body of the casket includes fixtures to be used for carrying the casket, these fixtures 3 being designed to be constructed of non-corrosive metal, there being bolts 4 for holding the fixtures to the wall of the casket, with suitable rubberized gaskets interposed between the large 100 flat heads of the bolts and the inside wall of the casket, to insure holding the handles

or fixtures in place, and yet affording a fluid-tight casket.

The cover or lid is fitted with a suitable plate-glass 5 which may be left plain if desired, or which may be frosted.

The cover 2 may be also constructed of any suitable metal, preferably pressed steel heavily coated or surfaced with porcelain enamel.

10 The body of the casket has a marginal roll or flange 6, which may be any size. This flange or roll is arcuate in cross section. In other words, it is concaved from its under face.

15 The cover or lid may be any suitable shape and is preferably provided with a rolled flange or rim formed marginally about the cover, which is also arcuate corresponding to the arcuate shape of the rim or flange 6, 20 in order to conform thereto. However, the arcuate marginal flange or rim 7 of the cover overlies the flange or rim 6 a substantial distance, depending downwardly as shown more clearly at 8 in Figure 3. This depending 25 part 8 of the rim or roll or flange of the cover at suitable locations is provided with slots 9, and between the slots with resilient tongues 10, the purpose of which will hereinafter appear.

30 Interposed between the marginal rolls, arms or flanges 6 and 7 is a suitable packing or gasket or sealing means 11, of any suitable material, either rubberized asbestos or rubberized fabric, or the like, preferably 35 the latter, in order to insure a tight joint between the rolls or rims of the body and cover of the casket.

Passing through the rims or rolls of the body and the cover of the casket and at locations incident to the resilient tongues 10 (it being possible to use any number) are bolts 12, preferably provided with flat heads 13, which engage the upper face of the flange 7 of the cover. The shanks of the bolts pass 45 through the two rims and through the packing. The shanks of the bolts have opposite sides cut away causing flat extensions 14 to be formed, and 15 denotes a lever, the head portion 16 of which is bifurcated as shown at 50 17. The bifurcation 17 receives the flat extension 14 of the shank of the bolt, that is to say, when the lever is mounted in position. The head 15 of the lever consists of the opposite disk walls 18, which are notched at 55 19. The bottoms of the notches 19 are constructed off-center or eccentric to the center of the disk walls, the notches adapted to engage a transverse pin 20 carried by the flat extension 14 of the shank of the bolt. Due to the 60 eccentricity of the crotches or bottoms of the notches 19, the disk walls operate as cams or eccentrics, when the lever is moved to fastening position. When the lever 15 is moved into fastening position, the 65 walls or cams engage with the under face of

the rim, roll or flange 6 of the body of the casket, the cams acting to draw the two flanges, rims or rolls 6 and 7 toward each other, clamping the packing 11 tightly between the flanges, thereby insuring a substantial seal hermetically between the rims, also insuring a fluid-tight joint. The lever 15 when in fastening position has its free end 21 engaged with the under face of the tongue 10, closely in position with a shoulder 75 22 on the under face of the tongue. The fact is, when the free end 21 of the lever is so engaged a portion of the body of the lever engages the under edge 23 of the rim or roll 6, thereby limiting the lever in its movement to insure a fastening position.

Where the flat extension 14 merges from a portion of the shank, shoulders 24 are caused to be formed. These shoulders constitute limiting means to prevent the notches 19 from disengaging the transverse pin 20, that is to say, when the lever is in rocking position and the bolt removed from the rims or rollers. Reference is made to the fastening position in this instance to mean a position at right angles to the bolt, when the bolt is removed. However, when the bolt 12 is removed, it is possible to move the lever to a position just opposite to that shown in Figure 3, so as to permit removal of the lever 15, from engagement with the pin 20.

90 The cover or lid of the burial casket may be made in various designs, and is fitted with a hermetically sealed plate-glass. However, the cover may be left plain. This construction of burial casket will permit of burials without the use of rough boxes, cement sarcophagus and the like, or other preparation, unless such may be considered as a matter of choice.

100 The invention having been set forth, what is claimed is:

1. The combination with conforming rims on the adjacent marginal edges of a body and a cover of a burial casket including a packing between the rims, a bolt passing through the conforming rims and the packing and provided with means to engage the under face of the rim of the body to draw the two rims together, means for holding the tightening means in fastened position, said bolt including opposite shoulders, and means carried by the bolt consisting of eccentrically mounted cams adapted to engage with said shoulders, when said means engage with the under face of one of the rims to limit disconnection of such means from the bolt, when the fastening means is in a position at right angles to the bolt, a position such as used to prevent detachment of such means.

115 2. The combination with conforming rims of a burial casket and cover therefor, including a packing between the two rims, a bolt passing through the rims and the packing, a device removably pivoted on the shank of

the bolt and provided with means for engagement with the under face of the rim of the body to draw the two rims together, means for retaining the device in fastened position, said last mentioned means consisting of a lever arm, the rim of the cover having a spring tongue including a shoulder, with which shoulder and the tongue the lever may be held locked in a fastened position, and means for limiting the lever arm 10 in engagement with the shoulder of said tongue.

In testimony whereof I affix my signature.
IRA IRVING INMAN.
